To all whom it may concern:

Be it known that I, LOUIS STROHACKER, a citizen of the United States, residing at Freeport, in the county of Stephenson and State of Illinois, have invented a new, original, and ornamental Design for a Toy Riding Car, of which the following is a specification, reference being had to the accompanying drawing, forming part thereof.

The figure is a perspective view of a toy riding car showing my new design.

I claim:
The ornamental design for a toy riding car as shown.

LOUIS STROHACKER.
